O. N. TEVANDER

SEALING MEANS FOR RECEPTACLES

Filed July 2, 1923

Inventor:
Olof N. Tevander
By L. A. Gray Atty.

UNITED STATES PATENT OFFICE.

OLOF N. TEVANDER, OF CHICAGO, ILLINOIS, ASSIGNOR TO STANDARD CAP & SEAL CORPORATION, OF CHICAGO, ILLINOIS, A CORPORATION OF VIRGINIA.

SEALING MEANS FOR RECEPTACLES.

Application filed July 2, 1923. Serial No. 649,158.

To all whom it may concern:

Be it known that I, OLOF N. TEVANDER, a citizen of the United States, residing at Chicago, in the county of Cook and State of Illinois, have invented a certain new and useful Improvement in Sealing Means for Receptacles, of which the following is a full, clear, concise, and exact description.

My invention relates to the sealing of closure caps for milk bottles or other containers and resides in a novel relationship between a constricting string surrounding the cap neck and sealing wax, glue, or other suitable cement or adhesive substance which is employed to maintain the approached ends of the string in assembly.

In the preferred embodiment of the invention the ends of the string are merely crossed without being tied and the cement is applied to the string where their ends cross to perform the function of a knotting of the crossed ends, this knotting being preferably omitted, though the invention is not to be thus limited.

In the preferred embodiment of the invention a piece of paper or other suitable sheet material is interposed between the crossed ends of the string and the skirt of the cap and the cement is applied to the crossed ends of the string and the outer face of said sheet material which acts as a guard to prevent the cement from reaching the skirt of the cap.

In the most preferred embodiment of the invention the guard of sheet material is initially coated with the cement and is located in place between the crossed ends of the string and the cap skirt with the cement thereon facing outwardly. The guard is then folded upon itself to bring the portions of its cement bearing face together. The cement is preferably of such a nature that it will not harden until heated or subjected to other temperature change or is subjected to pressure, or to both heat and pressure, whereby the guards may be carried in stock ready for use. By suitably marking or forming the seal in a distinctive manner, undetectable reuse of the cap is prevented. When the peculiar cement is employed it is not to be limited to use in conjunction with guards.

The invention will be more fully explained by reference to the accompanying drawing in which Fig. 1 is a perspective view of the

upper portion of a milk bottle with the cap in place together with a guard of sheet material between the crossed ends of the string and a patch of suitable cement applied over the crossed ends of the string and upon the outer face of the guard, which is shown unfolded in this figure; Fig. 2 shows the guard of Fig. 1 folded; Fig. 3 shows an arrangement somewhat similar to that shown in Fig. 1 but with the cement initially disposed upon the outer face of the guard before it is used; Fig. 4 illustrates the guard of Fig. 3 folded; Fig. 5 is an enlarged sectional view taken on line 5-5 of Fig. 4; and Fig. 6 is a sectional view on line 6-6 of Fig. 4.

Like parts are indicated by similar characters of reference throughout the different figures.

The container 1, which is illustrated as a milk bottle, is formed with a bead 2 surrounding the mouth thereof and is desirably furnished with a seat 3 within the bead upon which a closure disc 4 may be placed.

The closure cap 5 is placed upon the bottle with its skirt 6 surrounding the bottle and extending below the bead 2. This cap skirt is desirably fluted, but the invention is not to be thus limited.

The portion of the skirt that is to be held contracted beneath the bead after the bottle has been filled is so contracted with the aid of suitable string 7, preferably non-metallic, that is passed about and drawn tightly against the cap skirt in a zone beneath the bead. The ends of the string are crossed or approached and preferably untied and are held together by a patch or body of cement 8, which is desirably so applied that it will not come in direct contact with the skirt. To the latter end a guard 9 of paper or other suitable sheet material is placed against the cap before the string is applied, and the string has its ends crossed over the guard. The guard may be initially uncoated with cement, in which case the cement is applied after the string is applied, as illustrated in Fig. 1, whereafter the guard is folded as illustrated in Fig. 2. The cement, being initially fluid or plastic, will flow around the crossing of the string and secure a firm mechanical union between the string and cap. The cement is of such a nature that it will harden upon squeezing the sides of the folded guard toward each other by means of a suitable squeezing tool, and preferably in

the presence of a suitable degree of heat applied thereto.

- In the form of the invention illustrated in Figs. 3 to 6 inclusive, the cement is initially applied to the guard and is desirably of such a nature that it will remain sufficiently fluid or plastic until suitable heat or pressure is applied, or both heat and pressure are applied, whereby the guards with such cement thereon may be carried in stock. The guard, with such cement thereon, is placed against the cap skirt with the coated side thereof facing outward whereafter the string is crossed over it as illustrated in Fig. 3. The guard is then folded and the sides thereof pressed together in the presence or absence of heat, as preferred, to effect a firm assemblage of guard and string as illustrated in Figs. 4, 5 and 6.
- 20 The seal may have a suitable trade mark or other indication thereon to guard against an undetectable reapplication of string to the cap skirt with the aid of a fraudulent seal.
- 25 The cement employed is preferably a phenol formaldehyde resin such as bakelite. The term cement is used in the sense of any substance, which, by hardening, will adhere to objects to which it is applied.
- 30 Having thus described my invention, I claim as new and desire to secure by Letters Patent the following:
1. The combination with a container; of a skirted cap placed over the opening there-
35 in with the skirt thereof surrounding the container; a string passed about the cap skirt and having its ends approached; and a body of cement applied to the approached ends of the string, said cement being of a
40 nature requiring application of pressure thereto to harden.
2. The combination with a container; of a skirted cap placed over the opening there-
45 in with the skirt thereof surrounding the container; a string passed about the cap skirt and having its ends approached; and a body of cement applied to the approached ends of the string, said cement being of a
50 nature requiring application of pressure and heat thereto to harden.
3. The combination with a container; of a skirted cap placed over the opening there-
55 in with the skirt thereof surrounding the container; a string passed about the cap skirt and having its ends approached; and a body of cement applied to the approached ends of the string, said cement being of a
60 nature requiring application of heat thereto to harden.
- 60 4. The combination with a container; of a skirted cap placed over the opening there-
65 in with the skirt thereof surrounding the container; a string passed about the cap skirt and having its ends approached; a
70 guard between the cap and the approached ends of the string; and a body of cement applied to the guard and the approached ends of the string, said cement being of a
75 nature requiring the application of pressure thereto to harden.

70 ends of the string; and a body of cement applied to the guard and the approached ends of the string, said guard being folded upon itself with the cement between the sides of its fold.

5. The combination with a container; of a skirted cap placed over the opening there-
in with the skirt thereof surrounding the container; a string passed about the cap skirt and having its ends approached; a
75 guard between the cap and the approached ends of the string; and a body of cement applied to the guard and the approached ends of the string, said cement being of a
80 nature requiring the application of pressure thereto to harden.

6. The combination with a container; of a skirted cap placed over the opening there-
in with the skirt thereof surrounding the container; a string passed about the cap skirt and having its ends approached; a
85 guard between the cap and the approached ends of the string; and a body of cement applied to the guard and the approached ends of the string, said guard being folded upon itself with the cement between the sides of its fold, said cement being of a
90 nature requiring the application of pressure thereto to harden.

7. The combination with a container; of a skirted cap placed over the opening there-
in with the skirt thereof surrounding the container; a string passed about the cap skirt and having its ends approached; a
95 guard between the cap and the approached ends of the string; and a body of cement applied to the guard and the approached ends of the string, said cement being of a
100 nature requiring the application of pressure and heat thereto to harden.

105 8. The combination with a container; of a skirted cap placed over the opening there-
in with the skirt thereof surrounding the container; a string passed about the cap skirt and having its ends approached; a
110 guard between the cap and the approached ends of the string; and a body of cement applied to the guard and the approached ends of the string, said guard being folded upon itself with the cement between the
115 sides of its fold, said cement being of a nature requiring the application of pressure and heat thereto to harden.

120 9. The combination with a container; of a skirted cap placed over the opening there-
in with the skirt thereof surrounding the container; a string passed about the cap skirt and having its ends approached; a
125 guard between the cap and the approached ends of the string; and a body of cement applied to the guard and the approached ends of the string, said cement being of a
nature requiring the application of heat thereto to harden.

10. The combination with a container; of

- 5 a skirted cap placed over the opening there-
in with the skirt thereof surrounding the
container; a string passed about the cap
skirt and having its ends approached; a
5 guard between the cap and the approached
ends of the string; and a body of cement
applied to the guard and the approached
ends of the string, said guard being folded
upon itself with the cement between the
10 sides of its fold, said cement being of a
nature requiring the application of heat
thereto to harden.
11. The combination with a container; of
a skirted cap placed over the opening there-
15 in with the skirt thereof surrounding the
container; a string passed about the cap
skirt and having its ends approached; and
a body of cement applied to the approached
ends of the string, said cement being of a
20 nature requiring application of pressure and
change of temperature thereto to harden.
12. The combination with a container; of
a skirted cap placed over the opening there-
25 in with the skirt thereof surrounding the
container; a string passed about the cap
skirt and having its ends approached; and
a body of cement applied to the approached
ends of the string, said cement being of a
30 nature requiring application of change of
temperature thereto to harden.
13. The combination with a container; of
a skirted cap placed over the opening there-
35 in with the skirt thereof surrounding the
container; a string passed about the cap
skirt and having its ends approached; a
guard between the cap and the approached
ends of the string; and a body of cement
40 applied to the guard and the approached
ends of the string, said cement being of a
nature requiring the application of pressure
and change of temperature thereto to
harden.
14. The combination with a container; of
a skirted cap placed over the opening there-
45 in with the skirt thereof surrounding the
container; a string passed about the cap
skirt and having its ends approached; a
guard between the cap and the approached
ends of the string; and a body of cement
50 applied to the guard and the approached
ends of the string, said guard being folded
upon itself with the cement between the
sides of its fold, said cement being of a
nature requiring the application of pressure
55 and change of temperature thereto to
harden.
15. The combination with a container; of
a skirted cap placed over the opening there-
60 in with the skirt thereof surrounding the
container; a string passed about the cap
skirt and having its ends approached; a
guard between the cap and the approached
ends of the string; and a body of cement
65 applied to the guard and the approached
ends of the string, said cement being of a
nature requiring the application of change
of temperature thereto to harden.
16. The combination with a container; of
a skirted cap placed over the opening there-
70 in with the skirt thereof surrounding the
container; a string passed about the cap
skirt and having its ends approached; a
guard between the cap and the approached
ends of the string; and a body of cement
75 applied to the guard and the approached
ends of the string, said guard being folded
upon itself with the cement between the
sides of its fold, said cement being of a
nature requiring the application of change
80 of temperature thereto to harden.

In witness whereof, I hereunto subscribe
my name this 20th day of June A. D., 1923.

OLOF N. TEVANDER.
